UNITED STATES PATENT OFFICE.

MATTIE O'MARROW, OF PARIS, TEXAS.

DESIGN FOR A CHURN-FRAME.

SPECIFICATION forming part of Design No. 30,797, dated May 16, 1899.

Application filed April 20, 1899. Serial No. 713,797. Term of patent 7 years.

To all whom it may concern:

Be it known that I, MATTIE O'MARROW, a citizen of the United States, residing at Paris, in the county of Lamar and State of Texas, ⁵ have invented and produced a new and original Design for a Churn-Frame, of which the following is a specification, reference being had to the accompanying drawings, forming part thereof.

10 Figure 1 is a perspective view of a churn-frame, showing my new design; and Fig. 2 is a side elevation thereof.

As shown in the drawings, the leading feature of my design is a horizontal base B, having at one edge a vertical upright flat standard A, on top of which is an upwardly-projecting elongation a ; flat side pieces C C at the edges of the standard A and at right an-

gles to the same and also to the base B, and having symmetrically-curved front edges; a ²⁰ horizontal table D, joining onto the standard A and lying on top of the side pieces C C, and having a slotted overhanging projection, and an arm E, joining onto the table D and vertical elongation a at the angle between them, ²⁵ and having an overhanging and slotted upper end.

Having thus described my invention, what I claim as new is—

The design for a churn-frame substantially ³⁰ as herein shown and described.

MATTIE O'MARROW.
